UNITED STATES PATENT OFFICE

JAMES CARTER, OF EUREKA, OHIO.

TRICYCLE.

SPECIFICATION forming part of Letters Patent No. 450,001, dated April 7, 1891.

Application filed May 8, 1890. Serial No. 351,004. (No model.)

To all whom it may concern:

Be it known that I, JAMES CARTER, a citizen of the United States, residing at Eureka, in the county of Gallia and State of Ohio, have 5 invented certain new and useful Improvements in Tricycles; and I do hereby declare the following to be a full, clear, and exact description of the invention, such as will enable others skilled in the art to which it appertains to

make and use the same.

This invention relates to road-vehicles which are especially designed to be propelled by the weight of the rider, and has for its object to provide a simple, compact, and efficient 15 device by which the power will be transmitted to the driving-wheels in the best possible manner and with the least loss of force.

The improvement consists in the novel features and peculiar construction and combination of the parts, which hereinafter will be 20 more fully described and claimed, and which are shown in the accompanying drawings, in which—

Figure 1 is a perspective view of a vehicle 25 embodying my invention. Fig. 2 is a side view, parts being broken away, of the vehicle. Fig. 3 is a top plan view of the invention. Fig. 4 is a section on the line X X of Fig. 3, showing the operation by dotted lines. Fig. 30 5 is a detail top plan and side view of one of the pawl-carrying levers.

The frame comprises the side bars A, the end bar a, and the converging end a', in which is journaled the fork B, in which is journaled 35 the steering-wheel b. This fork is provided at its upper end with the bar b', from the ends of which extend the rods b² forward within convenient reach of the rider. The wheels C are journaled loosely on the axle c, 40 and are provided on their inner sides with disks or rims D, which are in engagement with the driving-wheels E, that are keyed on the ends of the shaft e, which is journaled in standard a², projecting upward from the side bars A. The ratchet-wheel F, which is keyed 45 on the shaft e, is operated on by the two sets of pawl-carrying levers G G', which have their inner ends loosely connected with the said shaft b, and which are forked and straddled on said ratchet-wheel. The pawls g g' 50 are pivoted between the members of the forked levers G G' and are held in engagement with

the said ratchet-wheel by the springs h h', which are secured to the closed ends of the said levers G G', which extend in diametrical 55 opposite direction and are connected with the opposite ends of the seat-bar i in the following manner: The forked lever G' is connected with the rear ends of the seat i by the rod i', and the forked lever G is connected with the 60 front end of the said seat-bar i by the hanger i², rod i³, and the link i⁴, said rod i³ being connected midway of its ends with the standard a³, by the pivot i⁵, which passes through said standard a³, and an arm i⁶, which projects up 65 from the rod i³. By this construction it will be seen that the said levers G and G' move in unison in opposite direction, so that only one is in active position at a time.

The seat I is provided with a depending leg- 70 section J, which is adapted to rock on the cross-bar j, extending between the side bars A.

The driving-wheels E may be keyed with the disks or rims D in any suitable manner, the frictional contact shown being the pref- 75 erable form, in that it will permit a slipping of the one on the other in abnormal strain.

The operation of the invention is as follows: The rider, sitting on the seat I, rocks the same to and fro by means of the connection 80 hereinbefore specified, between the ends of the seat-bars and the pawl-carrying levers, rocks the same on the shaft e, and turns the said shaft e and the driving-wheels E thereon, which wheels E impart their motion to 85 the wheel C through the rims or disks D and propel the vehicle.

Having thus described my invention, what I claim, and desire to secure by Letters Patent, is—

1. In a vehicle propelled by manual power, the combination, with the shaft e, geared with the supporting-wheels of the vehicle and having the ratchet-wheel F keyed thereon, and the swinging seat having bar i, of the independent levers G and G', mounted on shaft e and having pawls g and g', which engage with the ratchet-wheel F, the rod i', connecting the rear end of bar i with the lever G', the lever i², pivoted to swing bodily in the arc of a circle, the rod i³, connecting one end of lever i² with the lever G, and the rod i⁴, connecting the other end of the lever i³ with the front end of the bar i, substantially as set forth. 95 100

2. In a vehicle propelled by manual power, the combination of the wheels C, having rims D, the shaft e, having drive-wheels E E, which are in engagement with the rims D, the ratchet-wheel F on the shaft e, the oppositely-acting levers G and G', mounted on the shaft e and having pawls g and g', respectively, which are in engagement with the ratchet-wheel F, the swinging seat having bar i, the rod i', connecting the rear end of bar i with the lever G', the lever i'', having arms i''' midway of its ends by which it is pivotally sup-

ported to swing longitudinally, the rod i⁴, connecting lever G with the rear end of lever i³, and the rod i², connecting the front end of lever i³ with the front end of the said bar i, substantially as set forth.

In testimony whereof I affix my signature in presence of two witnesses.

JAMES CARTER.
